UNITED STATES PATENT OFFICE

STEPHEN J. ATTINGER, OF SHARPSBURG, PENNSYLVANIA

DESIGN FOR A PICTURE FRAME

Application filed July 29, 1930. Serial No. 36,509. Term of patent 7 years.

To all whom it may concern:

Be it known that I, STEPHEN J. ATTINGER, a citizen of the United States, residing at Sharpsburg, in the county of Allegheny and State of Pennsylvania, have invented a new, original, and ornamental Design for a Picture Frame, of which the following is a specification, reference being had to the accompanying drawing, forming part thereof.

frame where section 4 is taken, viewing the frame from one side at an angle of approximately forty-five degrees as indicated by the arrow in Figure 4.

The ornamentation as shown on the bottom panel of the frame extends entirely around the face of the frame.

I claim:

The ornamental design for a picture frame, as shown and described.

STEPHEN J. ATTINGER.
